Patented July 23, 1918.

FIG. 1.

FIG. 2.

FIG. 3.

FIG. 4.

Inventor:
Edward D. Priest,
by *Alfred D. Davis*
His Attorney.

UNITED STATES PATENT OFFICE.

EDWARD D. PRIEST, OF SCHENECTADY, NEW YORK, ASSIGNOR TO GENERAL ELECTRIC COMPANY, A CORPORATION OF NEW YORK.

TORPEDO.

1,273,668.

Specification of Letters Patent. Patented July 23, 1918.

Application filed November 11, 1916. Serial No. 130,891.

To all whom it may concern:

Be it known that I, EDWARD D. PRIEST, a citizen of the United States, residing at Schenectady, county of Schenectady, State of New York, have invented certain new and useful Improvements in Torpedoes, of which the following is a specification.

Dropping a missile from an aeroplane with sufficient accuracy that it will hit a ship is a very difficult matter, and the number of hits registered is only a small proportion of the missiles dropped. One of the objects of my invention is to facilitate the destruction of a target such as a ship by means of a torpedo dropped from an aeroplane by causing the torpedo after it strikes the water to move in some predetermined path of motion, such as a spiral, so that if the torpedo strikes the water somewhere near a target, it will, in the course of its movement, come into contact with it. To this end successively adjacent or parallel portions of the course should not be separated by a space substantially greater than that occupied by the object to be attacked.

In one form of my invention I provide a rudder for the torpedo and connect this rudder to the propelling mechanism in such a manner that the position of the rudder may be constantly varied so as to cover the desired area. I also provide some means such as rudders of peculiar construction which will close the propelling motor circuit when the torpedo strikes the water. In order to prevent the contact device from exploding the torpedo when it strikes the water, I place the contact device on the end of the torpedo and make the contact device and the end of the torpedo of such small area that very little pressure will be exerted on the contact device when the torpedo strikes the water. To prevent the torpedo from sinking in the water to too great a depth when it is dropped from an aeroplane, I may also provide a parachute which will permit the torpedo to drop gradually at a diminished rate of speed, and be disengaged from the torpedo as soon as it strikes the water.

Referring to the drawings which show one embodiment of my invention, Figure 1 shows an aeroplane adapted to carry a torpedo and having means controlled by the

operator from his seat for releasing the torpedo when desired; Fig. 2 is a vertical sectional view of the torpedo showing some of the parts in elevation; Fig. 3 is a horizontal sectional view of the torpedo showing some of the parts in elevation; Fig. 4 is a diagrammatic representation of the path of travel which the torpedo may be set to pursue after it strikes the water; Fig. 5 is a view showing the torpedo suspended from a parachute, and Fig. 6 is a view showing in detail the mode of suspension.

Referring now to Fig. 1 of the drawing, I have diagrammatically indicated an aeroplane at 10 having suitable propelling means indicated at 11. The torpedo 12 is shown as suspended from beneath the aeroplane having a hand operated lever and releasing device 13 and 14 operatively connected as at 15 so that the torpedo may be readily released at will by the aviator or pilot seated in the body of the aeroplane. It is, of course, obvious that the torpedo need not be suspended from beneath the aeroplane but may be mounted for discharge in any approved or convenient manner.

The torpedo 12 embodying my invention is constructed more particularly as shown in Figs. 2 and 3. It is constructed with the usual shell 16, in the head of which is carried the usual charge of explosive at 17 and adapted to be detonated by the usual firing pin, as shown at 18. This firing pin, as before pointed out, is arranged so as not to discharge the torpedo on contact with the water. To this end it is made relatively small and mounted centrally in the head of the torpedo so that the pressure of the water on it will be as small as compatible with the design of torpedoes generally.

The torpedo 12 is provided also with the usual propeller indicated at 19 adapted to be driven by motor 20 through the instrumentality of shaft 19'. The motor 20, as shown, is electrical and adapted to be supplied with electrical energy from any convenient source, shown here as a battery 21, which may be either primary or secondary. Of course any other suitable form of motor may be employed if desired.

In order that the torpedo may be set in motion as soon as it alights on the surface of the water, it is preferable to release it in such manner that it strikes the water

held first, hence I have provided rudders 22 and 22' of special design such that when the torpedo plunges into the water, they are deflected, thereby transmitting motion to 5 the motor controlling circuit closer 23 for bridging the circuit across terminals 23', whereupon the circuit being completed through the motor 20, it is set in motion.

It is thus seen that as soon as the torpedo 10 strikes the surface of the water, the motor 20 is started, driving the torpedo forward in a predetermined course depending on the initial setting of the rudders 24 and 24'. Such a torpedo as I have described is 15 sometimes called an automobile torpedo.

Inasmuch as it is difficult to strike a target from an aeroplane, as before pointed out, I have provided means which will enable the torpedo when it alights on the 20 surface of the water to advance in all directions over the adjacent surface, so that if the torpedo strikes the water anywhere near the neighborhood of the target, it will almost certainly be struck before the torpedo 25 has run its course.

The most effectual path known to me at present for accomplishing this end is the spiral. To this end I have provided means for gradually and uniformly decreasing the 30 deflection of the rudders 24 and 24' as the torpedo advances upon its course. I have provided the gearing indicated at 25 to turn the rudders 24 and 24', which gearing is uniformly driven by pinion 26 mounted on 35 the motor driven shaft 19' through a reducing gear 27 and shafting 23'.

It is thus seen that I have provided effectual means for causing the torpedo 12, when it once alights on the water, to advance steadily over a given area in a spiral path, as shown in Fig. 4, where it will sooner or later come into contact with its target, frequently a ship, as indicated at 8.

It will be readily understood by those 45 skilled in the art that I may design my torpedo so that it will displace any desired amount of water enabling it to ride on the surface of the water, or, if desired, to advance partially or wholly submerged.

Notwithstanding this feature of its design, it may happen that the torpedo will plunge far under the surface of the water 50 due to its accelerated descent from the aeroplane which launched it. In order to avoid this initial plunge into the water by the torpedo, since it may deter it from effectually reaching its target, I may provide a parachute 30, as shown in Fig. 5. This parachute is disengageably attached to the torpedo 12 by jaws 31 which engage loop 32, more clearly shown in Fig. 6, which loop is 55 made fast to some convenient point on the torpedo. The jaws 31 are pivoted at 33 to the under structure of the parachute 30 and are forced tightly together by the wedging

action of the inserted tongue 34 carried by float operated rod 35. It is thus seen that as the torpedo descends into the water, the float operated rod 35 will remove the tongue 34 from between the jaws 31. The jaws thus 70 will open releasing loop 32 so that the parachute will fall away from the torpedo as it alights on the water in such a manner as not to interfere with the progress of the torpedo as it seeks its target.

While such a parachute may be advantageous in the practice of my invention, it is by no means essential to a torpedo launched from an aeroplane to advance toward its target in the predetermined manner which I 80 have disclosed.

While I have above described in detail the best means at present known to me for carrying out an embodiment of my invention, I would have it understood that I do not mean to be limited thereby in the choice of mechanical equivalents and the embodiment of means to an end except as delineated in my appended claims.

What I claim as new and desire to secure 90 by Letters Patent of the United States, is:—

1. An automobile torpedo provided with means whereby when it is released in the vicinity of an object to be attacked it will cover an area by advancing on substantially 95 parallel lines which are separated by a space not substantially greater than that occupied by the object whereby if the object is within the area covered by the torpedo it will be struck.

2. An automobile torpedo provided with means whereby when it is released in the vicinity of an object to be attacked, it will describe a spiral in which the turns are separated by a space not substantially greater than that occupied by the object, whereby if the object is within the area covered by the spiral it will be struck.

3. An automobile torpedo provided with a rudder for steering it when released in the vicinity of an object to be attacked and means for continuously deflecting said rudder in one direction so that the torpedo will describe a spiral in which the turns are separated by a space not substantially greater than that occupied by the object to be attacked.

4. An automobile torpedo provided with motor driven propelling and steering devices arranged to cause the torpedo to describe a spiral in which the turns are not separated by a space greater than that occupied by an object to be attacked and means deflected by the surface of the water for setting said motor driven devices in motion.

5. An automobile torpedo provided with an electrically driven propelling device and steering means geared thereto in such manner as to cause the torpedo to describe a spiral in which the turns are separated by a

space not substantially greater than that occupied by the object to be attacked.

6. The combination with a dirigible automobile torpedo having a driving motor, of means operated when the torpedo strikes the water for starting the driving motor, a steering rudder, and connections between the

rudder and the driving motor for gradually and uniformly varying the position of the rudder to cause the torpedo to advance in a **10** spiral path to cover a prescribed area.

In witness whereof, I have hereunto set my hand this 10th day of November, 1916.

EDWARD D. PRIEST.
